UNITED STATES PATENT OFFICE.

GARRY J. DORMANDY, OF TROY, NEW YORK, ASSIGNOR OF ONE-HALF TO UNITED SHIRT AND COLLAR COMPANY, OF TROY, NEW YORK, A CORPORATION OF NEW YORK.

ELECTRIC-LIGHTING FIXTURE.

1,300,827.

Specification of Letters Patent. Patented Apr. 15, 1919.

Application filed June 28, 1917. Serial No. 177,456.

To all whom it may concern:

Be it known that I, GARRY J. DORMANDY, a citizen of the United States, residing at Troy, county of Rensselaer, State of New York, have invented certain new and useful Improvements in Electric-Lighting Fixtures, of which the following is a specification.

My invention relates to new and useful improvements in electric-lighting fixtures, and more particularly of that character or type adapted to support an electric lamp on a work bench, table or other support, or in operative relation to the same, although the invention is capable of use in other situations wherever applicable.

The invention consists in the novel construction of parts, and the arrangement thereof in operative combination, to be more fully described hereinafter, and the novelty of which will be particularly pointed out and distinctly claimed.

I have fully and clearly illustrated two embodiments of my invention, in the accompanying drawings, to be taken as a part of this specification, and wherein—

Figure 1 is a view in front elevation of a lighting fixture embodying my invention;

Fig. 2 is a section on the line 2—2 of Fig. 1;

Fig. 3 is a detailed view of one of the elements shown in Figs. 1 and 2;

Fig. 4 is a detailed view in front elevation of a modification of the structure shown in Fig. 3.

Referring to the drawings by characters of reference:

1 designates a distributing or outlet box, preferably rectangular in form, and comprising a rear vertical wall 2, top and bottom horizontal walls 3, 4, parallel to each other, and at right angles to said rear wall, and vertical end walls 5, 6, parallel to each other and at right angles to said rear wall and said top and bottom walls. This box may be made of metal or any suitable material. The front of the box is provided with an opening 7, adapted to be closed by a removable cover plate 8, preferably of porcelain or other insulating material. The cover plate 8 is held in position to close said opening 7 by means of fastening screws 9, let through suitable openings 9^a in said plate, and threaded at their inner ends into lugs 10 on the inner faces of said walls 3, 4. 55 The plate 8 is provided with openings 8^a for passage of electric conductors to the interior of the box.

In the form of the invention shown in Fig. 1, the bottom wall 4 of said distributing or outlet box is provided with an external downwardly projecting attaching device, preferably in the form of a cylindrical nipple 11, which is internally threaded at 12 to receive the threaded upper end of a vertical standard 13. The standard 13 may be, and preferably is, provided with a suitable base or foot 14 adapted to rest on and be secured to the work table or other support indicated generally at 15. The standard 13 may, or 70 may not, be tubular, according to whether or not it is employed as a conduit for electric conductors. The nipple 11 is preferably held in place on the wall of the box by inserting one end of said nipple through an 75 opening 4^a in said wall, and swaging or expanding said thread on the inner face of said wall, as indicated at 11^a in Fig. 2 of the drawings.

The end walls of the box are each provided with an attaching device, preferably in the form of a nipple 16, each of which nipples is held in place by passing an end thereof through an opening 5^a or 6^a in the end wall, and swaging or expanding said 80 end over on the inner face of said wall, as indicated at 16^a in Figs. 1, 2 and 3 of the drawings. These nipples 16 are internally threaded as at 17 to receive the threaded ends of horizontal members 18, 19, respectively, preferably in the form of pipe sections or flat tubular members. The opposite end of the member 19 from that which is connected to the box 1 is connected to a vertical standard 20 by means of the angle 95 nipple or coupling 21 at the upper end of said standard, the lower end of the standard having a foot 22 to rest on the table 15, or other support. The opposite end of the member 18 from that connected to the nipple 16 may be likewise connected to a support or standard (not shown), similar to the standard 20, or may be connected to the nipple 16 of another box 1 (not shown) 100 similar to the box 1 heretofore described. It will be noted that the arrangement of the standards 13, 20, and the members 18, 19, for supporting the box 1 provide an ef-

fficient and simple means for supporting one or more of said boxes at desired intervals along a work bench or table.

Projecting upward from the top wall 3 of 5 the box 1 is a cylindrical bearing pin or stud 23, which may be tubular if desired, and secured in place on said wall by passing an end of the stud through an opening 3^a in the wall and swaging or expanding said ends 10 over on the inner face of said wall at 23^a. At this point I would state that the particular manner described for securing the nipples 11, 16, and the stud 23 on the respective walls of the box 1 is preferable and efficient, 15 but is not obligatory, as other means may be employed for the purpose without departing from the spirit and scope of my invention.

24 designates a swivel bracket comprising 20 angularly disposed members 25, 26, preferably disposed at right angles to each other, and each including a split sleeve, the arms or members 24^a, 25^a, of which are provided at their free ends with apertured ears 27, 25 28, respectively, and apertures of which receive adjusting or clamping screws 29, 30, by which the arms of each member may be adjusted toward and away from each other. The opening between the arms 25^a of the 30 member 26 is adapted to receive the said bearing pin or stud 23, and the arms are adapted to tightly engage the said pin, the degree of engagement being determined by adjustment of the screw 30, whereby the 35 bracket member is rotatably adjustable or movable about the said pivot member or stud 23, so that it may be turned on the latter and will be frictionally held in the position to which it is adjusted. The arms 24^a of 40 the member 25 are adapted to receive a cylindrical pivot member or pin 31, carried on the rear face of the part 31^a, having oppositely disposed arms 32 carrying apertured guide sleeves 33 in alignment with 45 each other, and through the apertures of which is slidably and rotatably carried a supporting member, preferably in the form of a rigid tube 35, at one end of which is carried a key socket 36 for an incandescent lamp bulb 37. The conductors 38 for the 50 lamp preferably pass through one or more of the vertical standards 13 or 20 and within the outlet box, and are connected with the lamp by flexible conductors 39 passing through one of the openings 8^a, heretofore 55 described, and which are inserted in the rear end of the tube 35, through which they pass to the lamp socket, as shown in Fig. 1.

The arms 24^a of the member 25 are 60 clamped in strong frictional engagement by means of the screw 29, with the said pin 31 so that the member 31^a may be adjusted pivotally, but will be held in any position to which it is adjusted.

65 It will be seen from an examination of

Figs. 1 and 2 that the swivel member is horizontally rotatable on the member 23 to provide for lateral or rotary adjustment of the lamp bulb about the longitudinal vertical axis of the standard 13, and the rotation of the part 31^a on a horizontal axis in the vertical member 25 of the swivel bracket provides for the vertical adjustment of the lamp bulb 37; that is the member may be located at different elevations. 75

In the modified form shown in Fig. 4 the construction is substantially the same as that heretofore described, except that this form is adapted to be used without individual support by means of a standard similar to the standard 13, and for this reason the attaching device 11, or its equivalent, is omitted. This form of the invention is adapted to be inserted at any point in the pipe line 18, 19, as indicated in the drawings. 85

The pivot member 23 is preferably internally threaded, as at 23^b, to receive an externally threaded plug 23^c which may be in the form of a bushing, and the upper end 90 of which is adapted to be located above the lower portion of the member 31^a, so that the part 31 will be prevented from slipping out of engagement with the part 25. The part 31^a preferably extends below the upper 95 edge of the said plug 23^c, as is clearly shown in Fig. 2 of the drawings. If it is desired to remove the part 31^a from engagement with the part 25, the plug may be screwed down into the pivot 23 until the upper edge 100 of said plug is low enough to permit movement of the part 31^a above the upper end of said plug in a direction lengthwise of the pivot member 31. The plug may have sockets 23^d to be engaged by a spanner wrench 105 for screwing the plug in and out of the pivot stud 23.

From the above description taken in connection with the drawings it will be seen that I have provided a simple and effective 110 arrangement for supporting the swivel member of the lamp fixture directly upon the outlet or distributing box, and for supporting the latter without cumbersome and complicated supporting means. It will also be 115 seen that I have provided an arrangement wherein the electric feed wires or conductors leading to the distributing box are supported and concealed above, and free from, the supporting table, so that there is no likelihood 120 of said conductors being in the way of the work on the table or the operatives engaged in the work.

I have not shown and described any specific wire connections in the distributing box, 125 as it will be understood these can be supplied readily by those skilled in the art.

The specific form of the swivel coupling is not specifically claimed herein, but is the subject matter of a separate application, 130

Serial No. 158,801, filed by me under date of March 31, 1917.

What I claim and desire to secure by Letters Patent of the United States is—

5. 1. In combination, a distributing box, an opening therein through which electric conductors may be brought into the box, an attachment secured to the box, an electric light fixture removably mounted on said attachment and having universal movement with respect thereto, and a removable cover on 20 said box provided with an opening through which electric conductors may be taken from said box.
10. 2. In combination, a distributing box, an opening therein through which electric con- 25

ductors may be brought into the box, an attachment secured to the box, an electric light fixture removably mounted on said attachment and having universal movement with respect thereto, and a removable cover on 20 said box provided with an opening through which electric conductors may be taken from said box.

In testimony whereof I have hereunto signed my name in the presence of two sub- 25

scribing witnesses.

GARRY J. DORMANDY.
